DESIGN FOR A GLOVE

Lucille J. Maclear, New York, N. Y., assignor to
Van Raalte Company, Inc., New York, N. Y., a
corporation of New York

Application November 27, 1935, Serial No. 59,797

Term of patent 3½ years

To all whom it may concern:

Be it known that I, Lucille J. Maclear, a citizen of the United States, residing at New York, county and State of New York, have invented a new, original, and ornamental Design for a Glove, of which the following is a specification, reference being had to the accompanying drawing, forming a part thereof.

Figure 1 is a back view of a glove embodying my new design, and

Figure 2 is a front view of the glove embodying the new design.

The entire glove, with the exception of the three transverse bands, consists of a ribbed fabric, while the edging and the bands consist of a fabric of different texture. The cuff is further characterized by the addition of six balls presenting a light reflecting appearance.

I claim:

The ornamental design for a glove, as shown and described.

LUCILLE J. MACLEAR.
